(57) **CLAIM**

The ornamental design of an adjustable and collapsible bed frame as shown and described.

DESCRIPTION

FIG. 1 is a perspective view of an Adjustable and Collapsible Bed Frame, showing my new design in a first configuration of use as a Queen size bed;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side view thereof, shown inverted;

FIG. 7 is a right side view thereof;

FIG. 8 is a perspective view of the Bed Frame of FIG. 1, showing my new design in a second configuration of use as a King size bed;

FIG. 9 is a top plan view thereof;

FIG. 10 is a bottom plan view thereof;

FIG. 11 is a front elevation view thereof;

FIG. 12 is a rear elevation view thereof;

FIG. 13 is a left side view thereof, shown inverted;

FIG. 14 is a right side view thereof;

FIG. 15 is a perspective view of the Bed Frame of FIG. 1, showing my new design in a third configuration of use as a Twin size bed;

FIG. 16 is a top plan view thereof;

FIG. 17 is a bottom plan view thereof;

FIG. 18 is a front elevation view thereof;

FIG. 19 is a rear elevation view thereof;

FIG. 20 is a left side view thereof, shown inverted;

FIG. 21 is a right side view thereof;

FIG. 22 is a perspective view of the Bed Frame of FIG. 1, showing my new design in a fourth configuration of use as a Full size bed;

FIG. 23 is a top plan view thereof;

FIG. 24 is a bottom plan view thereof;

FIG. 25 is a front elevation view thereof;

FIG. 26 is a rear elevation view thereof;

FIG. 27 is a left side view thereof, shown inverted;

(Continued)

FIG. 28 is a right side view thereof;
 FIG. 29 is a perspective view of the Bed Frame of FIG. 1, shown in a partially collapsed configuration;
 FIG. 30 is a top plan view thereof;
 FIG. 31 is a bottom plan view thereof;
 FIG. 32 is a front elevation view thereof;
 FIG. 33 is a rear elevation view thereof;
 FIG. 34 is a left side view thereof, shown inverted;
 FIG. 35 is a right side view thereof;
 FIG. 36 is a perspective view of the Bed Frame of FIG. 1, shown in a fully collapsed configuration;
 FIG. 37 is a top plan view thereof;
 FIG. 38 is a bottom plan view thereof;
 FIG. 39 is a front elevation view thereof;
 FIG. 40 is a rear elevation view thereof;
 FIG. 41 is a left side view thereof, shown inverted;
 FIG. 42 is a right side view thereof;
 FIG. 43 is a perspective view of the Bed Frame of FIG. 1, shown in a compact storage configuration;
 FIG. 44 is a top plan view thereof;
 FIG. 45 is a bottom plan view thereof;
 FIG. 46 is a front elevation view thereof;
 FIG. 47 is a rear elevation view thereof;
 FIG. 48 is a left side view thereof, shown inverted; and
 FIG. 49 is a right side view thereof.
